[57] CLAIM

The ornamental design for a rotatable rack for compact discs, as shown and described.

DESCRIPTION

FIG. 1 is a front-top perspective view of a rotatable rack for compact discs, showing my new design;

FIG. 2 is a front elevational view thereof;

FIG. 3 is a rear elevational view thereof;

FIG. 4 is a right elevational view thereof, the left elevational view being a mirror image thereof;

FIG. 5 is a top plane view thereof;

FIG. 6 is a bottom plane view thereof; and,

FIG. 7 is a cross-sectional view taken generally along sectional lines 7—7 in FIG. 2.

FIG. 1

FIG. 2

FIG. 4

FIG. 5

FIG. 6

FIG. 3

FIG.7
